ELECTRORESPONSIVE DEVICE

Herbert C. Graves, Jr., East Bradford Township,
Chester County, Pa., assignor to I-T-E Circuit
Breaker Company, Philadelphia, Pa., a corpo-
ration of New Jersey

Application April 6, 1934, Serial No. 719,327

32 Claims. (Cl. 200—88)

My invention relates to electroresponsive devices and, while the devices of my invention are of general application in the control of electric circuits, systems and devices, they are particularly suitable for effecting the tripping of automatic circuit breakers.

More specifically, my invention is directed to electroresponsive devices which, when associated with an electric control circuit or system, will substantially instantaneously effect a controlling operation in response to excessive or severe abnormal circuit conditions as, for example, overloads occasioned by short circuits, and which will, in addition, effect a similar controlling operation upon the occurrence of moderate abnormal circuit conditions obtaining for a predetermined time. Preferably, the time delay in the second-named operation is roughly dependent upon the time-intensity characteristic of the abnormal circuit condition. For example, the device may operate within a predetermined time interval in response to moderate overloads, and after only a slightly shorter interval upon the occurrence of heavier, but less than the aforesaid excessive, overloads such as may be occasioned by motor-starting operations.

In accordance with one embodiment of my invention, an electroresponsive device suitable for controlling, either directly or indirectly, an electric circuit, system or device, comprises a conventional electromagnet with a movable armature biased to a normal position and movable, in response to energization of the electromagnet, to an operative position. The armature is additionally biased to its normal position by a movable member and/or an additional biasing spring for increasing the energization of the electromagnet required to move the armature to its operative position. Means are provided normally interconnecting the armature and the additional biasing means. When the energization of the electromagnet attains this increased magnitude, due to short circuits or severe abnormal conditions on the controlled circuit, the armature and its associated biasing means are substantially instantaneously moved to operative position.

There is provided also additional means responsive to moderate abnormal circuit conditions and effective after a time delay to release the additional biasing means, whereupon only the normal biasing force acts upon the movable armature, and such moderate abnormal conditions effect its movement to its operative position. This time delay means preferably com-

prises a thermal element and a separate heater therefor, heated in accordance with the energization of the electromagnet, as by inductively coupling the heater or its circuit with the core structure thereof. The time constants of the device under different magnitudes of abnormal conditions may be modified by proportioning the magnetic core structure to saturate under certain conditions, this saturation being effective also to protect the thermal element from excessive heating or electrodynamic strains or distortion.

Both the instantaneous operation of the device, in response to excessive overloads, and the time delay operation, in response to moderate overloads, are independently adjustable. If desired, a suitable indicating scale and pointer may be associated with the adjustable connection between the thermal element and the armature latch to indicate the time delay for which the device is adjusted. This indicating means may also be adjustable to compensate for variations in ambient temperature.

For a better understanding of my invention, together with other and further objects thereof, reference is had to the following description taken in connection with the accompanying drawings, and its scope will be pointed out in the appended claims.

Referring now to the drawings, Fig. 1 is a view in front elevation of a three-pole automatic circuit breaker controlled by an electroresponsive device embodying my invention, while Fig. 2 is a view in side elevation of the apparatus of Fig. 1;

Fig. 3 is a view in side elevation of an electroresponsive device embodying my invention;

Figs. 4, 5 and 6 are detailed perspectives of certain of the operating elements of Fig. 3;

Fig. 7 is an exploded view of the member interconnecting the thermal element and the armature latch, together with the associated indicating scale and pointer;

Figs. 8 and 9 are perspectives of the thermal element heater alone and in association with the thermal element, respectively;

Fig. 10 is a perspective of the adjustable latch-releasing link, while Fig. 11 is a cross-sectional view showing the manner of engagement of this link with the thermal operating member;

Figs. 12 and 13 are perspectives of a modified form of thermal element heater and of such a heater associated with the thermal element, respectively; while Fig. 14 is a schematic diagram of the essential elements of my improved elec-

troresponsive device, together with their circuit connections to an automatic circuit breaker; and Fig. 14a is a schematic diagram of certain elements of my invention applied to a direct current circuit breaker.

Referring now more particularly to Figs. 1 and 2 of the drawings, there is shown a 3-pole automatic circuit breaker, of a conventional type, comprising a base or panel member 10 and three movable contact assemblies 11, one for each pole of the breaker, cooperating with suitable stationary contact structure mounted on the panel 10. The movable contact assemblies 11 may be operated to circuit-closing position by any suitable automatic or manual closing mechanism, although I have illustrated, by way of example, an operating handle 12 and suitable linkage mechanism 13 including a common operating member 14 which may be interconnected with the handle 12 by the latch 15, and which may be secured in circuit-closed position by operating the links 13-14 to an overcenter position. The latch 15 may be released by a pivotally mounted trigger arm 16 disposed to be operated by any of the three electroresponsive devices 17, each associated with, and connected in circuit with, one pole of the automatic circuit breaker. The electroresponsive devices are effective, also, to break the several toggles 13-14 under certain conditions as described more fully hereinafter.

The structural features of the electroresponsive devices are shown more clearly in Fig. 3 et seq.

Referring to Fig. 3, it will be seen that the device 17 comprises a magnetic core structure 18 secured to a panel or base member 19 and provided with a suitable energizing coil 20. The magnetic circuit of the core structure 18 is open at one side, and cooperating with this open portion of the circuit, or air gap, is an armature 21 journaled on a pivot 25 supported from the base or panel 19. To prevent chattering of the armature at the pivot 25, it is provided with a detent 22 resting on a knife edge or other suitable pivot 23 spring supported from a bracket 23a secured to the base 19 and maintaining the pivoted end of the armature in its attracted position and in firm engagement with the pivot 25. The armature 21 is biased to the position shown in Fig. 3 by its own weight and/or by additional biasing springs, if required.

Under normal operating conditions, the armature 21 is restrained by additional biasing means comprising a carriage or roughly U-shaped bracket 24 pivoted on base 19 at 25 substantially coaxial with the pivot of the armature 21. The carriage 24 is connected with the armature 21 through a latch 26 which is provided with a detent engaging a spring extension 21a of the armature 21, adjustable as by a thumb screw 21b. The latch 26 is pivotally mounted in the outer end of the carriage 24, as at 29, and is biased into engagement with the extension 21a by a spring 27 attached to an arm 28 of the latch 26. The details of the latch 26 may be seen clearly in Fig. 5. The wedge shaped detent of the latch 26 and the spring 27 ensure a firm engagement between the upper detent surface 26b and the upper surface of the armature extension 21a. The carriage 24 is provided with an upwardly projecting member 24a, Fig. 4, which may be a block of insulating material, and which forms a stop to limit the downward motion of the armature 21. The armature 21 is normally raised from the stop 24a, however, by the wedging

action of the latch detent, described above. The weight of the carriage 24 may be sufficient to provide adequate additional bias or, in certain instances, it may be desirable to provide also an additional biasing spring 30 which interconnects a projection 31 of the carriage 24 and a member 32 threaded upon an adjusting screw 33 supported in a bracket 34 secured to the base 19. By adjusting the screw 33, the member 32 may be moved upwardly or downwardly, changing the lever arm of the biasing spring 30 about the pivot 25 of the carriage 24 and thus varying the effective biasing force.

An adjustable stop 35 mounted in the bracket 36, which forms a portion of a rigid frame structure for the device, cooperates with a stop 37 secured to the carriage 24 and is effective to vary the initial air-gap of the magnetic core 18 and thus the energization of the coil 20 required to move the armature 21 to its operative position. A projection 36a secured to the frame or bracket 36 is disposed in the path of movement of the projection 26a of the latch 26, and cooperates therewith to release the latch upon a predetermined movement thereof. When the armature 21 is so moved to its operative position, it may directly effect the opening or closing of cooperating contacts or, as illustrated, it may strike a tripping rod 38 sliding in a suitable recess formed in the magnetic core 18, which, in turn, releases the latch 15 and breaks the toggle 13-14 to permit the opening of the breaker contacts.

The time delay operation of the device in response to moderate overloads is obtained by means of a bimetallic thermal element 39 and its associated heater element 40, the latter comprising a closed conductive loop, substantially rectangular in form, surrounding the magnetic core member 18 and inductively heated in accordance with the energization of the coil 20. The heater element has preferably substantially a plane surface and may conveniently be a sheet metal punching. The thermal element 39 and the heater 40 are supported, in intimate contact, at their upper ends by means of spring-biased screws 40c. Preferably, the thermal element is firmly secured to the supporting insulating block 40d by shoulders on the screws 40c which pass through openings in the heater element 40. This latter element is resiliently held in intimate contact with the thermal element 39 by the springs 40e surrounding the shoulders of the screws 40c.

The configuration of the thermal element 39 and heater element 40 may be seen more clearly by reference to Figs. 8 and 9. As shown in these figures, the thermal element 39 comprises a pair of bimetallic strips 39a and 39b substantially parallel to and in intimate contact with the outside arms 40a and 40b, respectively, of the heater element 40, and secured in intimate contact therewith by means of the spring-biased screws 40c. The lower free ends of the bimetallic strips 39a and 39b are interconnected by an operating strip or member 39c. The operating member 39c has an opening 39d in which is inserted one end of an operating rod 41 secured therein by a spring-pressed washer 41c, the rod 41 being provided with a shoulder 41a abutting against the member 39c.

A portion of the rod 41 is formed with a spiral thread 41b with which engages an operating link 42, the details of which are shown more clearly in Figs. 10 and 11. As shown in these figures, the link 42 is provided with upstanding projections or lugs 42a and 42b of such configuration

as to be threaded upon the rod 41. The link 42 has an opening or bore 42c disposed to engage and slide along the unthreaded portion of the rod 41. The link 42 has also an extending projection 42d engaging a slot 43 in a side plate 44 which may form a part of the enclosing and protective housing of the device. It will be clear that, by rotation of the rod 41, the link 42 will be moved longitudinally by its threaded engagement, rotation about the rod 41 being prevented by the projection 42d sliding in the slot 43. The link 42 is provided also with a longitudinally-extending projection 42e disposed to strike and disengage the latch 26 upon a predetermined deflection of the thermal element 39.

In order to vary the time delay in the operation of the thermal element and to compensate for variations in the ambient temperature, there is provided an adjustment for the operating link 42 shown in exploded view in Fig. 7. As there shown, an adjusting knob 45 cooperates with a member 46 having a central bore through which the unthreaded portion of the rod 41 freely slides. A pair of screws 47 are effective to secure a firm engagement between the members 45 and 46 between which are clamped an indicating dial or plate 48 and an index plate 49. The rod 41 is provided with one or more flats or non-circular surfaces at its outer end 41d which engage a similarly formed opening 49a in the index plate 49. The index plate 49 has a plurality of circumferentially-disposed openings 49b which cooperate with a spring-pressed index button 50a secured to the bracket 36 as by a plate 50. As indicated in Fig. 3, the knob 45 is provided with a recess 45a into and out of which the end 41d of the rod 41 freely moves. The indicating dial or scale plate 48 may be provided with a projection 48a cooperating with a fixed stop 51 to limit the adjustment of the thermal element and operating as an index pointer for the scale dial 48.

In Figs. 12 and 13 are illustrated modified forms of the thermal heater, designated as 40', alone and assembled with the thermal element 39. In this modified construction, the members 40a' and 40b' are bent into angles in which are disposed the bimetallic elements 39a and 39b, while the cross members of the element 40' are offset from the plane of the thermal element 39. By this means, a better thermal relation is secured between the heater element 40' and the thermal element 39.

In Fig. 14 is shown schematically the essential operating elements of my improved electro-responsive device, together with a circuit diagram of the connections when applied to an automatic circuit breaker, as shown in Figs. 1 and 2. From this diagram it will be seen that the coil 20 is connected directly in series with the contacts of the circuit breaker and thus is in series with the controlled circuit.

The heater element 40 is shown as its electrical equivalent of a resistance 52 connected in circuit with a coil 53 inductively coupled to the coil 20 by the magnetic core 18. The other elements are shown schematically substantially in the operative relationship of Fig. 3.

The operation of the above-described electro-responsive device will be best understood by reference to Figs. 3 and 14. If it be assumed, for example, that an excessive overload occurs on the circuit controlled by the circuit breaker, including the movable contact assembly 11, the energization of the coil 20 of the electromagnet 75 will be sufficient to attract the armature 21 which

is connected to the carriage 24 by the latch 26. The armature 21 and the carriage 24 initially move as a unitary structure, being restrained by the weight of the structure and the biasing spring 30. As soon as this unitary structure has travelled a short distance, however, the projection 26a of the latch 26 engages a projection 36a secured to the frame or bracket 36 and the latch 26 is disengaged from the armature 21, allowing a rapid, forceful attraction of the armature 21 by the magnetic core 18, the armature 21 striking a hammer blow upon the tripping rod 38 and unlatching the circuit breaker of Figs. 1 and 2. By releasing the additional biasing means by initial movement of the armature 21, it is then restrained only by its weight and a more effective tripping action may be obtained.

The magnitude of the overload required to move the armature 21 instantaneously to its operative position will be dependent, among other things, upon the normal air-gap between the armature and the core member 18, and upon the biasing effect of the spring 30. The former may be adjusted by means of the adjustable stop screw 35, while the latter can be varied by adjusting the screw 33 which moves the member 32 to vary the lever arm of the biasing spring 30 about the pivot 25.

On the other hand, if the overload upon the controlled circuit is a moderate one, it will be insufficient to move the armature 21 to its operative position against the restraining force of the additional biasing elements. Under these conditions, however, a current will be induced in the heating coil or element 40 which, for moderate overloads, will be roughly proportional to the magnitude of the load current. This heater element is in intimate contact with the bimetallic strips comprising the thermal element 39 and, after a predetermined time delay, dependent upon the thermal characteristics of the elements 39 and 40, the element 39 will be deflected by an amount sufficient to move the projection 42e of the link 42 into engagement with the latch 26 to release the latter. The overload condition will effect a sufficient energization of the coil 20 to attract the armature 21 to its operative position, striking the trip rod 38 and opening the circuit breaker.

In this connection, it is to be noted that a very small unlatching force is required from the thermal element 39. In the first place, the biasing spring of the latch 26 is connected to the lower end of the thermal element 39 so that, as it deflects to release the latch 26, the spring 27 is correspondingly released. In other words, the thermal element 39 is not loaded by the biasing spring of the latch 26 in releasing the latch.

The biasing spring 27 is effective to secure a firm engagement between the latch 26 and the extension 21a of the armature 21 at the latching surface 26b, due to the wedging action of the lower surface of the latch detent, and thus renders the overload latch substantially shockproof. The magnetic attraction upon the armature 21 periodically passes through zero with the alternating flux of the core 18 so that the frictional force at the latch surface 26b due to the attraction of the armature also periodically passes through zero. It is possible, therefore, for the thermal element 39 to store energy resiliently during that portion of the cycle of alternating flux when the frictional engagement at the latch surface is greater than the unlatching force of the thermal element and to operate the latch 26 at the point of zero flux, and thus zero frictional

force. By utilizing a minimum unlatching force, there is a minimum overtravel of the unlatching mechanism, and a comparatively short time will elapse between the tripping of the device in response to an overload and reengagement of the armature 24 by the latch 26, which permits resetting of the associated circuit breaker.

As stated above, in the case of moderate overloads, the heating of the element 40 is roughly proportional to the energization of the coil 30 so that the time delay in the unlatching of the device by the thermal element 39 is roughly inversely proportional to the magnitude of the overload; that is, the time-energization characteristic is constant. Under heavier overloads, however, the core member 18 is designed to partially saturate while under excessive overloads, such as short circuits, the core member 18 may be completely saturated. By way of example only, it may be stated that it has been found satisfactory to design the core member 18 for saturation between 175% normal rating (full load single phase current when applied to a three phase circuit) and 500% or 600% rating (corresponding to normal motor starting current) and preferably around 300% rating. As the saturation of the core member increases, the effective inductive coupling with the heating element 40 decreases with the result that the time delay in the operation of the thermal element decreases less rapidly than inversely as the magnitude of the overload, approaching a constant time delay as the core member 18 approaches complete saturation; that is, the time-energization constant increases in magnitude. This feature may be of advantage in connection with the starting of motors drawing a heavy saturating current.

In addition, the time delay for any particular value of overload may be adjusted by means of the adjusting knob 45 and its connected mechanism. An angular adjustment of the knob 45 rotates the threaded rod 41 correspondingly and moves the link 42 longitudinally of the rod 41, thus varying the movement required of the thermal element 39 to release the latch 26. The time delay will, of course, be dependent directly upon the extent of the movement required of the thermal element 39. This time delay adjustment, also, is substantially uninfluenced by vibration or shocks to the apparatus. Since the adjustment of the thermal element 39 is dependent upon the ambient temperature, an adjustment for such ambient temperature may be secured by loosening the screws 47 and moving the scale dial or plate 48 with respect to the other elements. The plate 48 and the projection 48a, cooperating with the stop 51 to limit the adjustment of the thermal element, will thus bear a different relationship to the operating rod 41 and link 42 for the same indication of the plate 48, to compensate for variations in ambient temperature.

As shown clearly in Figs. 8 and 9, the strips 39a and 39b are in intimate contact with the two sides of the heater coil 40 and are retained in such relationship by the spring-biased screws 40c (Fig. 3). By forming the heater coil 40 so that it diverges from the thermal element 39 in the direction of deflection, the intimacy of contact therebetween is increased upon deflection of the thermal element. This intimacy of thermal contact may be increased by the modification shown in Figs. 12 and 13 in which the sides of the heater coil 40' are bent to extend in the direction of deflection of the thermal strips 39a and 39b. By using separate heater and thermal

elements, rather than combining them into a single unitary structure, damage or distortion to the thermal element is prevented and each may be selected for characteristics particularly suitable to its functions. In addition, the time characteristics of the device may be changed merely by changing the heater coil to one of different resistance and thermal characteristics.

In Fig. 14a is shown a modified schematic diagram of certain elements of a circuit breaker as applied to a direct current circuit breaker. In this case, the thermal element 39 is connected directly in circuit with the circuit breaker contacts, either across a shunt, or directly in series, as illustrated. It will be understood that the structural arrangement of elements is similar to that of the preceding figures, and the principles of operation the same.

While I have described what I at present consider the preferred embodiments of my invention, it will be obvious to those skilled in the art that various changes and modifications may be made without departing from my invention, and I, therefore, aim in the appended claims to cover all such changes and modifications as fall within the true spirit and scope of my invention.

What I claim is:

1. An electroresponsive device comprising an electromagnet, an armature member therefor pivoted at one end and biased to a normal position and movable to an operative position in response to predetermined energization of said electromagnet, a movable member for additionally biasing said armature member to its normal position, a latch pivotally connected adjacent one end of one of said members and normally in latching engagement with the corresponding end of the other of said members and mechanically locking said members together, pivot means mounting opposite ends of said members in juxtaposition, and means for rotating said latch about its pivotal connection relative to one of said members to disengage said latch from the other of said members.

2. An electroresponsive device comprising an electromagnet, a pivoted armature member therefor biased to a normal position and movable to an operative position in response to predetermined energization of said electromagnet, a member movable co-pivotedly with said armature member including a spring for additionally biasing said armature member to its normal position, a latch supported by one of said members and normally in latching engagement with the other of said members, and overload means responsive to the energization of said electromagnet for moving said latch relative to its supporting member to disengage said latch from said other member.

3. An electroresponsive device comprising an electromagnet, a pivotally mounted armature therefor biased to a normal position and movable to an operative position in response to a predetermined energization of said electromagnet, means for additionally biasing said armature to its normal position including a pivotally mounted carriage, a latch mounted on said carriage and normally interconnecting said carriage and said armature for movement together, and time delay means responsive to the energization of said electromagnet for moving said latch relative to said carriage to release said armature.

4. An electroresponsive device comprising an electromagnet, an armature therefor biased to a

- normal position and movable to an operative position in response to a predetermined energization of said electromagnet, means for additionally biasing said armature to its normal position 5 including a spring, means including a disengageable member directly interconnecting said spring and said armature, time delay means responsive to the energization of said electromagnet for disengaging said member and means operable upon 10 a predetermined movement of said armature and said disengageable member towards said operative position to remove said additional bias from said armature.
5. An electroresponsive device comprising an electromagnet, a pivotally mounted armature therefor biased to a normal position and movable to an operative position in response to a predetermined energization of said electromagnet, means for additionally biasing said armature to 15 its normal position including a pivotally mounted carriage, a latch pivotally mounted at the outer end of said carriage and normally interconnecting said armature and said carriage for movement together, a biasing spring connected 20 to restrain said carriage, means for adjusting said biasing spring, and time delay means responsive to the energization of said electromagnet for releasing said latch.
6. An electroresponsive device comprising an electromagnet, an armature therefor biased to a normal position and movable to an operative position in response to a predetermined energization of said electromagnet, means including a latch engaging said armature and movable there- 25 with for additionally biasing said armature to its normal position to increase the energization of said electromagnet required to move it to its operative position, time delay means responsive to the energization of said electromagnet for releasing said latch and means effective, upon initiation of movement of said armature in response to said increased energization of said electromagnet, independently and positively to release said latch.
- 45 7. An electroresponsive device for an electric circuit comprising a supporting member, an operating member movable from a normal position to an operative position, means including a deflecting thermal element for controlling and imparting a time delay into the movement of said member, means securing one end of said thermal element in fixed position, a heating member energized upon current flow through said circuit for heating said thermal element, and resilient means for 50 biasing said heating member into intimate heat exchanging relation with said thermal element.
8. An electroresponsive device comprising an electromagnet, an armature therefor biased to a normal position and movable to an operative position in response to a predetermined energization of said electromagnet, means including a disengageable member normally engaging said armature and movable therewith for additionally biasing said armature to its normal position to increase the energization of said electromagnet required to move it to its operative position, a thermal element effective to disengage said member, and a heater for said thermal element comprising a closed conductive loop surrounding the core of said electromagnet.
- 60 9. An electroresponsive device comprising an electromagnet, an armature therefor biased to a normal position and movable to an operative position in response to a predetermined energization
- of said electromagnet, means including a disengageable member normally engaging said armature for additionally biasing said armature to its normal position to increase the energization of said electromagnet required to move it to its operative position, a deflecting thermal element effective to disengage said member, and a heater for said thermal element comprising a closed conductive loop surrounding the core of said electromagnet and in intimate contact with said thermal element, said heater being shaped to conform approximately to the shape of said thermal element when deflected, whereby the intimacy of contact therebetween is increased upon deflection of said thermal element.
- 10 11. In an electroresponsive device, a thermal control mechanism comprising a bimetallic thermal element, a heating coil formed by a closed conductive loop for heating said element, means securing one end of said element in intimate contact with a part of said coil, a portion of said element being movable and another part of said coil extending in the direction of movement of said movable portion of said element when heated thereby to maintain said coil and element in close heat exchanging relation during said movement of said movable portion of said element.
- 15 12. In an electroresponsive device, a thermal control mechanism comprising a substantially rectangular heating coil, a pair of bimetallic strips disposed in intimate contact with two arms of said rectangular coil and secured at one end, and an operating member interconnecting said strips at their free ends.
- 20 13. In an electroresponsive device, a thermal control mechanism comprising a substantially rectangular heating coil, a pair of bimetallic strips disposed in intimate contact with two arms of said rectangular coil and secured at one end, said coil being shaped to diverge from the free ends of said strips when undeflected in such a direction that the intimacy of contact therebetween is increased upon deflection of said strips, and an operating member interconnecting said strips at their free end.
- 25 14. In an electroresponsive device including an electromagnet, a thermal control mechanism comprising a substantially rectangular closed conductive loop surrounding the core of said electromagnet, a pair of bimetallic strips disposed in intimate contact with two arms of said loop and secured at one end, and an operating member interconnecting said strips at their free ends.
- 30 15. In an electroresponsive device including an electromagnet having a core section saturable within the range of operation of the device, a thermal control mechanism comprising a flat bimetallic thermal element, a single closed conductive loop surrounding said saturable core section, a portion of said single loop extending parallel to said thermal element and disposed in intimate heat exchanging relation therewith.
- 35 16. In an electroresponsive device including an electromagnet having a core section saturable within the range of operation of the device, a

thermal control mechanism comprising a substantially rectangular closed conductive loop surrounding the saturable core section, and a pair of bimetallic strips disposed in intimate contact with two arms of said loop and secured at one end, and an operating member interconnecting said strips at their free ends.

17. In an electroresponsive device, a thermally controlled latching mechanism comprising a latch member operable from a latching position to a releasing position, a deflecting thermal element for operating said latch member to said releasing position and a spring for biasing said latch to said latching position and for simultaneously biasing said thermal element for deflection in the direction to release said latching member, said spring after movement of said latching member to said releasing position being operative to bias said latching member to said latching position.

18. An electroresponsive device comprising an electromagnet, an armature therefor biased to a normal position and movable to an operative position in response to a predetermined energization of said electromagnet, means including a latch engaging said armature for additionally biasing said armature to its normal position to increase the energization of said electromagnet required to move it to its operative position, a deflecting thermal element heated in accordance with the energization of said electromagnet, an operating member one end of which is operatively associated with said thermal element and the opposite end of which is operatively associated with said latch, said thermal element upon a predetermined deflection thereof moving said member, to release said latch, and a spring interconnecting said latch and said element for biasing said latch into said engagement and toward the corresponding end of said member and for biasing said element and said member toward said latch so that upon deflection of said thermal element the bias on said latch is not increased.

19. An electroresponsive device comprising an electromagnet, an armature therefor biased to a normal position and movable to an operative position in response to a predetermined energization of said electromagnet, means including a latch engaging said armature for additionally biasing said armature to its normal position to increase the energization of said electromagnet required to move it to its operative position, a deflecting thermal element heated in accordance with the energization of said electromagnet, a spring interconnecting and biasing together said thermal element and said latch independently of the position of said armature, and an operating member connected to said thermal element and effective, upon a predetermined deflection thereof, to release said latch.

20. An electroresponsive device comprising an electromagnet, an armature therefor biased to a normal position and movable to an operative position in response to a predetermined energization of said electromagnet, means including a latch engaging said armature for additionally biasing said armature to its normal position to increase the energization of said electromagnet required to move it to its operative position, a deflecting thermal element heated in accordance with the energization of said electromagnet, an operating member connected to said thermal element, and a link adjustably connected to said operating member and movable therewith to release said latch.

21. An electroresponsive device comprising an electromagnet, an armature therefor biased to a normal position and movable to an operative position in response to a predetermined energization of said electromagnet, means including a latch engaging said armature for additionally biasing said armature to its normal position to increase the energization of said electromagnet required to move it to its operative position, a deflecting thermal element heated in accordance with the energization of said electromagnet, a threaded rod connected to said thermal element and movable in response to deflection thereof, and an operating link engaging said threaded rod and movable therewith to release said latch.

22. An electroresponsive device comprising an electromagnet, an armature therefor biased to a normal position and movable to an operative position in response to a predetermined energization of said electromagnet, means including a latch engaging said armature for additionally biasing said armature to its normal position to increase the energization of said electromagnet required to move it to its operative position, a deflecting thermal element heated in accordance with the energization of said electromagnet, a threaded rod connected to said thermal element and movable in response to deflection thereof, an operating link engaging said threaded rod and restrained from rotation about said rod, said link being effective to release said latch upon movement by said thermal element, and means for adjusting the angular position of said rod to calibrate the device.

23. An electroresponsive device comprising a supporting frame including an electromagnet as a unitary part thereof, an armature for said electromagnet biased to a normal position and movable to an operative position in response to a predetermined energization of said electromagnet, means including a latch engaging said armature for additionally biasing said armature to its normal position to increase the energization of said electromagnet required to move it to its operative position, a deflecting thermal element heated in accordance with the energization of said electromagnet, a threaded rod connected to said thermal element and movable in response to deflection thereof, an operating link engaging said threaded rod and engaging a slot in said frame to prevent rotation thereof about said rod, said link being movable upon deflection of said thermal element to release said latch, and an adjusting member pivotally mounted on said frame and slidably engaging said rod, whereby adjustment of said member adjusts said rod, but said rod is freely movable longitudinally with respect to said knob.

24. An electroresponsive device comprising an electromagnet, an armature structure therefor biased to a normal position and movable to an operative position in response to a predetermined energization of said electromagnet, means including a latch engaging said armature structure for additionally biasing said armature to its normal position to increase the energization of said electromagnet required to move it to its operative position, resilient means independent of said biasing means for securing a firm engagement between said armature structure and the stop surface of said latch, and time delay means responsive to the energization of said electromagnet for releasing said latch.

25. An electroresponsive device comprising an electromagnet, an armature therefor biased to

- a normal position and movable to an operative position in response to a predetermined energization of said electromagnet, means including a latch provided with a stop surface engaging 5 said armature for additionally biasing said armature to its normal position to increase the energization of said electromagnet required to move it to its operative position, resilient means independent of said biasing means for securing 10 a firm engagement between said armature and said stop surface of said latch, and means responsive to the energization of said electromagnet for releasing said latch, said last-named means having a time delay in its operation decreasing substantially inversely with the energization of said electromagnet for magnitudes of energization below a predetermined value, said electromagnet including means for modifying 15 said time delay whereby it decreases at a less rapid rate for magnitudes of energization above said predetermined value.
26. An electroresponsive device for an electric circuit comprising a member biased to a normal position and movable to an operative position, 25 operating means responsive to the energization of said circuit for biasing said member to said operative position, the magnitude of said bias being proportional to the magnitude of the current flowing in the circuit, means including a 30 latch engaging said member and movable therewith for additionally biasing said member to its normal position to increase the energization of said operating means required to move it to its operative position, time delay means responsive 35 to the energization of said circuit for releasing said latch, and separate tripping means engaged by said latch after a predetermined movement of said member and said latch toward said operative position for positively releasing said latch 40 thereby to remove said additional bias whereupon said operating means is effective to move quickly said member to said operative position.
27. An electroresponsive device comprising an electromagnet, an armature therefor biased to a normal position and movable to an operative position in response to a predetermined energization of said electromagnet, means including a latch engaging said armature for additionally biasing said armature to its normal position to 50 increase the energization of said electromagnet required to move it to its operative position, a thermal element heated in accordance with the energization of said electromagnet, a connection between said thermal element and said latch for releasing the latter, means for adjusting said connection, an indicating scale associated with said adjusting means, and means for adjusting said scale to correct for variations in ambient temperature.
- 60 28. An electroresponsive device comprising an electromagnet, an armature therefor biased to a normal position and movable to an operative position in response to a predetermined energization of said electromagnet, means including 65 a latch engaging said armature for additionally biasing said armature to its normal position to increase the energization of said electromagnet required to move it to its operative position, a deflecting thermal element heated in accordance with the energization of said electromagnet, a threaded rod connected to said thermal element, an operating link engaging said rod and effective to release said latch upon deflection of said thermal element, means for restraining said link from rotation about said rod, a pivotally mounted adjusting member slidably engaging said rod for 10 angularly rotating the same, an indicating scale associated with said adjusting member, and means for adjusting said scale to correct for variations in the ambient temperature.
29. An electroresponsive device comprising an electromagnet, an armature therefor, a disengageable member normally restraining said armature in an inoperative position, and a thermal control mechanism for releasing said member including a thermal element, a manually operable adjusting member for said thermal element rotatable for a single revolution for adjusting the temperature at which said disengageable member is released, a position indicating dial cooperating with said adjustable member, and 20 a spring lock for said adjustable member.
30. An electroresponsive device comprising an electromagnet, an armature therefor biased to a normal position and movable to an operative position in response to a predetermined energization of said electromagnet, a deflecting thermal element effective to impart a time delay into the movement of said armature to operative position, means securing one end of said element in a fixed position, a member heated in accordance with the energization of said electromagnet, and resilient means for biasing said member into intimate heat exchanging relation with said thermal element.
31. An overload trip unit for a circuit interrupter comprising an electromagnet responsive to the energization of the circuit interrupter, an armature movable by said electromagnet through a given air-gap to trip said interrupter, a latch for restraining said armature against movement, means operable with a time delay for releasing said latch during normal overload conditions of the circuit, and separate means operable without a time delay for releasing said latch upon the occurrence of abnormal overload conditions of said circuit.
32. An electroresponsive trip unit for a switch connected in a circuit subject to changes in an electrical condition comprising an electromagnet energized from said circuit and provided with an armature movable to trip said switch, a latch for restraining said armature against movement, means responsive to said condition and operable with a time delay with changes in said condition below a predetermined value for releasing said latch, and separate means responsive to said condition and operable without a time delay with changes in said condition above a predetermined value for releasing said latch.
